Attorneys

UNITED STATES PATENT OFFICE.

LEE J. VOORHEES, OF BINGHAMTON, NEW YORK, ASSIGNOR TO NATIONAL CARBON COMPANY, INC., A CORPORATION OF NEW YORK.

ELECTRICAL SWITCH.

Application filed February 6, 1920. Serial No. 356,661.

To all whom it may concern:

Be it known that I, LEE J. VOORHEES, a citizen of the United States, residing at Binghamton, in the county of Broome and

5 State of New York, have invented certain new and useful Improvements in Electrical Switches, of which the following is a specification.

This invention relates to electrical switches 10 of a kind having a primary circuit-controlling mechanism, normally freely operable to open or close an electrical circuit, and having also a superior controlling or locking mechanism adapted, on proper manipulation, to place the primary mechanism in a 15 position to either open or close the circuit, as desired, and to retain the primary mechanism in such position until further manipulation of the secondary or locking mechanism. Such switches are applicable to electrical 20 apparatus in which there is a circuit which must, under certain operating conditions, be frequently opened and closed, and with a minimum of physical exertion, but 25 which, under certain other operating conditions, must be opened or closed for prolonged periods of time. In order to obtain the desirable facility of operation, the primary 30 circuit-controlling mechanism may take the form of a member which may be moved by the pressure of the thumb or finger, and it may be restrained by a spring so that it will always return to the same position when the pressure is removed. When 35 the above or a similar form of primary circuit-controlling mechanism is employed, the locking mechanism must be capable of replacing manual pressure on the primary circuit-controlling mechanism at times when 40 the primary mechanism is required to be maintained for prolonged periods in the position to which it can be forced by manual pressure. Since one manipulation of the locking mechanism suffices for a considerable 45 time, it is not necessary that this mechanism should be operable with the same facility as the primary circuit closing mechanism. Even when, as in the case assumed, the primary mechanism is held in one of its 50 positions by the tension of a spring, ease of operation requires that the tension should be so adjusted that the primary circuit-controlling mechanism will require only a slight pressure to move it against the tension of 55 the spring. Under these conditions, the pri-

mary mechanism is apt to be accidentally displaced from its spring-held position, and it is desirable to provide means which will maintain the position of the contacts in spite of an accidental pressure applied to the primary circuit-controlling mechanism. 60

The object of the invention is to provide a switch mechanism which will combine the functions recited above.

Examples of electrical apparatus in which 65 a very readily operable circuit-controlling mechanism together with means for more stably fixing circuit-controlling elements in certain positions will readily suggest themselves. Electric-motors driving drills, such 70 as dentist's drills, automobile trouble lamps connected to sources of current by extension cords, and switches used in making electrical measurements, in connection with such instruments as voltmeters, ammeters and 75 Wheatstone bridges may be here mentioned, but for the sake of illustration, the switch mechanism of the present invention will be described in connection with a portable self-contained battery hand lamp, of the 80 kind commonly known as "flash-lights."

An embodiment of the invention as applied to a common form of flash-light is shown in the accompanying drawings, in 85 which—

Fig. 1 is an elevation of a flash-light provided with the improved switch, looking down upon the switch.

Fig. 2 is an enlarged plan view of the switch as viewed from the interior of the 90 lamp-casing. The lamp-casing is omitted for the sake of clearness.

Figs. 3 and 4 are views similar to Fig. 2 but showing the switch in different positions.

Fig. 5 is a sectional view on line 5—5 of Fig. 2.

Fig. 6 is a similar section on line 6—6 of Fig. 3 and

Fig. 7 is a similar section on line 7—7 100 of Fig. 4.

Fig. 8 is a plan view of the push-button of the switch, looking at the bottom of the button.

Fig. 9 is an elevation of the push-button. 105

Fig. 10 is a plan view of the member (shown in Figs. 5, 6 and 7) forming the external rotatable element of the switch.

Fig. 11 is an elevation of the external ro- 110 tatable member.

Fig. 12 is a fragmental plan view looking down upon the escutcheon plate carrying the switch mechanism.

Fig. 13 is a plan view looking down upon 5 the contact-carrying member of the switch and.

Fig. 14 is an elevation of the contact-carrying member.

In the embodiment shown, the switch as 10 semblage is applied over an aperture in a flash-light casing 1. A conductor connects one terminal of the battery with some portion of the switch, such as the escutcheon-plate 2. One terminal of the filament of the 15 incandescent bulb is connected with the other terminal of the battery while the other terminal of the bulb is connected with a contact-strip 3, passing beneath the aperture in the casing 1 and hence beneath the switch. 20 When the external rotatable member 4 of the switch is in the position shown in Figs. 2 and 5, the spring 5 raises the push-button 6 to the position shown in Figs. 2 and 5 with the switch out of contact with the strip 3. 25 Pressure upon the push-button 6, exerted by the thumb or finger, will then depress the button and the contact 7 against the tension of the spring 5 until the contact 7 bears upon strip 3, when the lamp will be lighted. 30 Upon releasing the push-button, the spring will raise contact 7 off the strip 3, and the light will be extinguished in an obvious manner.

With the rotatable member 4 in the position shown in Figs. 3 and 6, the contact 7 is carried around to a point where it cannot come into contact with strip 3, whether the push-button 6 is in its raised or depressed position. The structure of the switch, as 35 will be hereafter explained, is such that rotation of the member 4 to this position forces the push-button 6 and contact 7 against the tension of the spring 5 to their depressed positions. Nevertheless, the lamp is not 40 lighted and cannot be lighted until the member 4 is rotated to another position.

When the rotatable member 4 is in the position shown in Figs. 4 and 7, the contact member 7 is on the same side of the aperture in the casing 1 as is the strip 3. Since 45 rotation to this position likewise forces the push button 6 and contact 7 to their depressed positions, the lamp is continuously lighted in this position of the switch and cannot be extinguished without rotating the member 4.

The structure of the parts which produce the effects above noted will now be described.

Stamped in the escutcheon plate 2 is a 50 boss in the form of a truncated cone, having the lateral walls 8 and the tabular upper base 9. The external rotatable member 4 has a flat circular portion 10 of the same size as the portion 9 of plate 2. In the assembled switch, the disc 10 always rests upon

the table 9. The disc 10 has a raised portion 11 around its periphery and also a skirt 12 conforming with the conical surface 8. This skirt may be suitably knurled or fluted so that it may be readily turned with the fingers.

The push-button 6 has at its edges projecting tongues of metal 13. In the assembled switch, these tongues pass through the arcuate slots 14 in member 4 and the arcuate slots 15 in the table 9. The tongues 13 occupy the entire slots 14 so that any rotation of member 4 will be imparted to push-button 6 and the contact-carrying member 16 which is rigidly attached thereto as will be hereafter explained. The slots 15, however are of greater length than slots 14 so that the member 4, the push-button 6 and the contact-carrying member 16 may all be rotated together through a considerable arc, the rotation being limited by the sides of tongues 13 reaching the ends of the slots 15.

The contact-carrying member 16 is shown in Figs. 13 and 14 and comprises a disc portion and a contact shoe 7. Notches 17 are provided in the edge of disc and these are entered by the narrow ends 18 of the metal tongues 13 which are integral with push-button 6. By crimping the ends 18 of the tongues, as shown in Figs. 5, 6 and 7, the contact member 7 is rigidly attached to the push-button 6. The push-button is fixed against rotation relative to the member 4 but may approach or recede from it, its travel in this direction being limited by the length of the broad portions of the metal tongues 13.

The projections 19 on the tabular portion 9, and the cavities 20 in the contact-carrying member 16 are provided for the purpose of depressing the contact shoe 7 against strip 3 when the member 4 is rotated to the position shown in Figs. 3 and 7. In the position shown in Figs. 2 and 5, the cavities 20 register with the projections 19, permitting disc 10 to come into contact with table 9, the push-button to rise to its elevated position and the contact shoe 7 to separate from the strip 3. This is the "flash" position of the switch and the lamp will be lighted only so long as the button is held by the operator in its depressed position. The angular relation between the cavities 20, the notches 17 in the edge of the member 16 and the shoe 7, on the one hand and the projections 19 and slots 15 on the other hand is such that when the projections and cavities register, the contact shoe 7 just extends over the edge of the strip 3 and the metal tongues 13 are centrally located in the slots.

If the member 4 is now rotated in either direction, projections 19 will no longer register with cavities 20 and as they move out of registry therewith, the sloping sides of the projections will act as cam-surfaces to

force down the member 16 carrying the contact shoe 7. The push-button 6 will of course be drawn down to its depressed position. If the rotation of member 4 was in the proper direction to carry contact-shoe 7 over strip 3, the simultaneous depression of the contact shoe will close the circuit and the lamp will burn as long as the member 4 is not moved. If the rotation of member 4 was in the opposite direction, contact shoe 7 will be carried away from strip 3 and the simultaneous depression of contact shoe 7 will be ineffectual to close the circuit.

It will thus be seen that when the member 4 is rotated as far as possible in one direction, the lamp will be lighted and can be extinguished only by rotating member 4. In its other extreme position, member 4 is beyond the limits of conductor 3 and it is impossible to light the lamp while the member remains in this position. When member 4 is in its median position, the lamp is lighted by pressing on the push-button and extinguished by releasing it.

As has already been indicated, the application of the switch is not restricted to flash-lights. Likewise, the illustrative example of an embodiment of the invention imposes no restrictions on the scope of the invention, the latter being defined solely by the appended claims.

I claim:

1. An adjustable switch mechanism comprising a contact, a fixed conductor below the plane of all portions of said contact, in an intermittently operable position of said switch, means for reciprocating the contact along a path which intersects the fixed conductor, means for positively depressing the contact and holding the same in engagement with the fixed conductor in a closed circuit position, and means for revolving the contact about an axis substantially parallel to its path of reciprocation to a position beyond the limits of the fixed conductor, wherein closing of the circuit is prevented.

2. A switch mechanism comprising a contact, a fixed conductor, means for reciprocating the contact along a path which intersects the fixed conductor, means for revolving the contact about an axis, and means, including a cam surface, for forcing the contact against the fixed conductor when the contact is revolved.

3. A switch mechanism comprising a contact reciprocable along a path which intersects a fixed conductor, a spring adapted to normally maintain the contact away from the fixed conductor, means for moving the contact along its path to bring it against the conductor, means for revolving the contact about an axis to a position beyond the limits of the fixed conductor, means for revolving the contact to a second position over the fixed conductor, and means for positively depressing and holding the contact against the fixed conductor when the contact is revolved to said second position.

4. A switch mechanism comprising a contact reciprocable along a path which intersects a fixed conductor, a spring adapted to normally maintain the contact away from the fixed conductor, means for moving the contact along its path to bring it against the conductor, means for revolving the contact about an axis substantially parallel to its path of reciprocation to a position beyond the limits of the fixed conductor, means for revolving the contact to a second position over the fixed conductor, and means, including a cam surface, for forcing the contact against the fixed conductor when the contact is revolved to said second position.

5. A switch mechanism comprising a push button carrying a contact, a conductor opposed to said contact, said contact having a working face of irregular outline, means for rotating said contact into a plurality of positions, and means for positively depressing said contact in one such position into continuing engagement with the opposed conductor, whereby permanent closure of the circuit is effected.

6. A switch mechanism comprising a conductor, a compressible contact opposed thereto, said contact being asymmetrical with respect to said conductor, means for rotating said contact to a position where its asymmetrical working face will be ineffective to connect with said conductor when actuation of the switch is to be avoided, or into a position where its asymmetrical working face will be in continuing engagement with said conductor, and means for positively depressing the contact into engagement with the conductor in said last-named position.

In testimony whereof, I affix my signature.
LEE J. VOORHEES.
